UNITED STATES PATENT OFFICE.

ELIHU THOMSON, OF SWAMPSIDE, MASSACHUSETTS, ASSIGNOR TO GENERAL ELECTRIC COMPANY, A CORPORATION OF NEW YORK.

ELECTRIC HEATER.

1,072,530.

Specification of Letters Patent.

Patented Sept. 9, 1913.

Application filed February 16, 1912. Serial No. 678,121.

To all whom it may concern:

Be it known that I, ELIHU THOMSON, a citizen of the United States, residing at Swampscott, county of Essex, State of Massachusetts, have invented certain new and useful Improvements in Electric Heaters, of which the following is a specification.

My invention relates to electric heating devices, and more particularly to such electric heating devices as comprise means for storing heat therein and for liberating the same when desired.

One of the objects of my invention is to provide a device of this character having a simple and inexpensive electric heating means which will possess a greater degree of regulability than that possessed by ordinary heating units. I attain this object by the use of an electric arc in connection with the heat storage mass. I prefer to have the storage mass constitute one electrode of the arc as by such arrangement the heat is very efficiently and rapidly stored.

Another object of my invention is to provide means for varying the amount of energy supplied to an electric heater according to the temperature of the same. I attain this object by the use in connection with a movable member, the position of which determines the energy supplied to the heater, of coils exerting different attractive effects on the said movable member and an arrangement whereby the relative resistances of the respective coils, and therefore the relative currents passing therethrough, are changed by variations in temperature of the heating device.

My invention will be better understood by reference to the drawings in which it is shown embodied in several specific forms.

In the drawings, Figure 1 is a vertical section of one form of heat storage stove embodying my invention; Fig. 2 is a similar view of a modification of the same; Figs. 3, 4 and 5 are partial sections of stoves having means for automatically regulating the current supplied to the arc; and Figs. 6, 7, 8, 9 and 10 are diagrams showing the circuits for the devices shown in Figs. 1, 2, 3, 4 and 5 respectively.

The stove shown in the drawing comprises a heating chamber having inner and outer walls 1 and 2, which may be of metal, and lagging 3 which may be asbestos or any

other good heat insulating material between the said walls. The top of the heating chamber is formed by the heat storage mass 4 which may be of iron, steel or any material having comparatively high specific heat, high specific gravity and high specific heat conductivity. The heat storage mass 4 is supported by the walls of the heating chamber from which it is separated by insulation 5, which may be of mica, or any other substance having good electrical and heat insulating properties. A cover 6 consisting of a hollow shell of thin sheet metal filled with insulation 7 which may be similar to lagging 3 is provided for the heat storage mass. A water jacket 8, as shown in Fig. 1, may surround the outer wall of the heating chamber so that any heat which may be conducted through the insulating walls of the said chamber may be utilized. The pipe connections 8¹ and 8² are provided for supplying water to and conducting the same from the water jacket. The supply terminal 9 is attached to the heat storage mass and projects through the walls of the surrounding vessel.

In the device shown in Fig. 1, the solenoid 10 is mounted on the bottom of the heating chamber. The solenoid coil used in this form of my invention is preferably a fire-proof edgewise winding or other structure capable of withstanding high temperature and having a sufficient drop to cause steadiness in the arc. The arc is formed between the storage mass 4 and the electrode 11 which in this case also acts as a core for the solenoid 10 and is therefore of iron or other magnetic material as shown in Fig. 1, or the electrode may be of carbon or the like and be supported by a holder 12 which may be the core of the solenoid and therefore be of magnetic material, as shown in Fig. 2. This electrode is counterbalanced by the weight 13 mounted upon one end of the lever 14 which is pivoted on the solenoid frame. To the other end of this lever is connected the core 11 by means of the rod 15. One end of the solenoid winding is connected to the terminal 16 which projects through the walls of the stove and the other end is attached to the case. When a suitable current is supplied to the apparatus, the solenoid magnet is adjusted by the position and amount of the weight 13 to draw an arc of a certain current strength or one

which involves the delivery of a certain amount of electrical energy. On account of the walls of the heating chamber being an excellent non-conductor of heat most of the 5 heat finds its way into the storage mass 4 and raises its temperature so that after a comparatively short time, say an hour or two, it is ready to be used. By removing the cover 6, a sauce pan or other cooking 10 vessel or anything which it is desired to heat may be placed therein and heat will be communicated very rapidly to it owing to the high conductivity of the storage mass. After the heating operation is completed the cover 6 may be again placed upon the storage mass and the temperature will again rise due to the heat delivered to the mass by the electric arc. Owing to the provision of good heat insulation around the storage 15 mass it will retain its heat for a long time after the current is cut off from it.

In Fig. 2 I have shown a modification in which the coil 10 is located outside of the heating chamber, the core 11 projecting into the same. This arrangement allows the 20 space between the bottom of the storage mass and the bottom of the heating chamber to be lessened, thus decreasing the radiating surface of the heating chamber. In this 25 modification the coil owing to its location need not be of heat resisting material but may be wound with ordinary insulated wire. A regulable spring 17 supported upon the bracket 18 attached to the solenoid may be 30 used to regulate the length of the arc and thus determine the amount of energy normally supplied thereto. A steadyng resistance 19 consisting of a flat coil with its turns open and separated from the bottom 35 of the heating chamber by suitable electrical insulation 20 may be used. This resistance may have a drop of from 20 to 30 volts on a 110 volt circuit for steadyng the 40 arc. The resistance 19, the regulating coil 45 10 and the storage mass 4 are preferably in series as shown in Fig. 7. In this modification the action of the apparatus may be observed from the outside and adjustment 50 may be made for different current strengths in the heating arc.

In Figs. 3, 4 and 5 I have shown thermo-electric regulating means for the arc. In Fig. 3 the upper coil 21 is of iron or any metal whose resistance has a high positive 55 temperature coefficient while the lower coil 22 is of German silver or any metal whose resistance has a comparatively low temperature coefficient. The magnetizable core 11 is so located with respect to the coils 21 and 60 22 that a given current exerts a greater pull in the lower coil 22 than in the upper coil 21. As shown in the diagram constituting Fig. 8, the current divides at the 65 terminal 16, part of it going through the upper coil and part of it through the lower

coil. These circuits then unite at the core 11 between which and the mass 4 the arc is formed. When a high temperature is reached in the heating chamber, more current is shunted through the lower coil than 70 through the upper coil owing to the increased resistance of the iron wire with the increase of temperature, and the lower coil being more effective in pulling down the core and drawing the arc, the current is weakened 75 in the whole system, and the delivery of energy is accordingly decreased. Inasmuch as the magnet coils are within the same general enclosure as the storage mass they are subjected to the same temperature. By locating the lower coil 22 outside of the heating chamber and the upper coil 21 within the same, as shown in Fig. 4, the same regulation may be secured and in such an arrangement it is not necessary to have the 80 coils of different metals. They can both be of iron, for example, or one of iron and the other of copper. In such an arrangement the current would be shunted from the hotter to the cooler coil.

In Fig. 5 I have shown an arrangement in which the coils 23 and 24 for controlling the length of the arc are located outside of the heating chamber. In this arrangement, the steadyng resistance 19 is also shown. 95 As shown in Fig. 10 the current after leaving the terminal 16 divides, one portion passing through the steadyng resistance 19 and the other through the outer coil 24. These circuits then unite and the current 100 then passes through the inner coil 23, the core 11 and the storage mass 4. The resistance 19 is of a material such as iron having a high temperature coefficient and when it reaches a high temperature more current 105 is shunted to the supplemental coil 24 which acts in conjunction with the coil 23 to extend the arc, thereby weakening the current and reducing the delivery of energy.

Various modifications of the structure disclosed will readily suggest themselves to those skilled in the art, and the same may be made without departing from the spirit of my invention, the scope of which is set forth in the annexed claims.

What I claim as new and desire to secure by Letters Patent of the United States, is,—

1. An electric heater comprising a heat storage mass, means for producing an electric arc for heating the same, and means for confining the heat generated by the arc to the storage mass.

2. An electric heater comprising a heat storage mass having good heat conductivity and constituting a wall of a heating chamber, heat insulating means constituting the remaining walls of the said chamber, and means for producing an electric arc within the said chamber for heating the said storage mass.

3. An electric heater comprising a heat storage mass constituting one wall of a heating chamber, heat insulating means constituting the remaining walls of the said chamber, and an electrode so disposed that an arc may be drawn in the said chamber between the electrode and the aforesaid heat storage mass for heating the latter.
4. An electric heater comprising a heat storage mass, means for producing an electric arc for heating the same, and means for automatically controlling the supply of energy to the arc according to the temperature of the storage mass.
5. A heater comprising a heat storage mass, an electrode adjacent thereto, means for producing an electric arc between the said electrode and the said heat storage mass, and means controlled by the temperature of the storage mass for regulating the amount of energy supplied to the arc.
6. In a heater, a storage mass forming one wall of a heating chamber, insulation forming the other walls, an electrode so disposed that an electric arc may be drawn between it and the storage mass within the heating chamber, and means controlled by the temperature of the heating chamber for regulating the amount of energy supplied to said arc.
7. In an electric heater, the combination of a heat storage mass, means for producing an electric arc for heating the same including a movable electrode, electro-magnetic means for controlling the position of the said electrode, and means for varying the effect of said electro-magnetic means according to the temperature of the storage mass.
8. An electric heater comprising a heat storage mass connected to one side of an electric circuit, an electrode associated therewith so as to draw an arc between the mass and the electrode, and means for confining the heat developed by the arc to the storage mass.
9. In a heating device, means for producing heat by the consumption of electric energy comprising a movable element, and means for controlling the amount of energy supplied to said heat producing means by varying the position of said movable element comprising a plurality of coils exerting different attractive effects thereon and means for controlling the current passing through the respective coils according to the temperature produced by the heating means.
10. In a heating device, a movable member, the position of which determines the amount of energy supplied to the device, and a controlling device for said movable member comprising coils having different attractive effect on the movable member, the resistance of certain of said coils being increased relative to each other by an increase in temperature of the heating device.

In witness whereof, I have hereunto set my hand this thirteenth day of February, 1912.

ELIHU THOMSON.
